STOKER FEED MECHANISM

Herbert E. Preston, Philadelphia, Pa., assignor to
 American Engineering Company, Philadelphia,
 Pa., a corporation of Pennsylvania

Application November 5, 1931, Serial No. 573,176

4 Claims. (Cl. 259—38)

This invention relates to improvements in
 stoker feed mechanism, and relates more par-
 ticularly to improved means for feeding fuel to
 the main rams of a multiple retort underfeed
 5 stoker of the general character disclosed in U. S.
 Patent No. 792,862.

A principal object of the invention is to pro-
 vide novel and improved mechanism insuring a
 uniform and uninterrupted passage of fuel from
 10 the coal hopper or hoppers to the said rams.

A more specific object of the invention is to
 provide positive means for preventing arching of
 coal in the hoppers interfering with free and
 regular movements of the fuel to the rams.

15 The invention further resides in certain novel
 structural features and details hereinafter set
 forth and illustrated in the attached drawings, in
 which:

Figure 1 is a front elevational and partial sec-
 20 tional view of the hopper of a multiple retort
 underfeed stoker made in accordance with my
 invention;

Fig. 2 is a side elevational and partial sectional
 view of the hopper;

25 Fig. 3 is a section on the line 3—3, Fig. 2, and
 Fig. 4 is a section on the line 4—4, Fig. 1.

With reference to the drawings, the hopper
 therein disclosed comprises a vertical rear wall 1
 which in assembly adjoins the front wall of the
 30 furnace, and upwardly and outwardly inclined
 front wall 2 and end walls 3 and 4. In the bot-
 tom, the hopper has a longitudinally extending
 series of openings 5 which respectively communi-
 35 cate with a corresponding series of ram cylinders
 6, these cylinders being formed in castings 7, to
 which the hopper is secured by means of bolts 8
 and clamps 9 and 10. The cylinders 6 are located
 40 well below the floor of the hopper and are con-
 nected through the openings 5 by passages 11
 formed in the said castings 7. Rams (not shown)
 are adapted to operate within the cylinders 6 in
 well known manner to force the fuel passing into
 45 the ram cylinders into the upper ends of the
 stoker retorts, and the usual crank shaft 12 is
 provided (see Fig. 3), to the various cranks 13
 of which the said rams are connected and which is
 rotated from a suitable source of power to actuate
 50 the rams.

The bottom of the hopper intermediate the
 openings 5 is formed with flat surfaces, each of
 which is provided with a wear plate 14 secured
 to the bottom of the hopper in the present in-
 stance by bolts 15, and each of these wear plates
 55 constitutes a bearing surface for a member 16
 which as shown in Fig. 4 extends completely

across the bottom of the hopper between the front
 and rear walls and which has rear and front edges
 conforming respectively to the vertical and in-
 clined rear and front walls of the hopper. The
 members 16 which are in the form in the present 5
 instance of open brackets have each a base portion
 17 of substantial width which rest upon the re-
 spective wear plates 14, and each of said members
 has a central boss 18 having a transverse cylin-
 drical opening for reception of a shaft 19 which 10
 extends longitudinally of the hopper and through
 the end walls 3 and 4, bearings 21, 21 for said
 shaft being provided at the outer faces of said
 walls. Each of the members 16 is secured to the
 shaft by means of a pin 22 which extends through 15
 the walls of the boss 18 and through holes in the
 shaft provided for their reception. The pins 22
 are tapered in the present instance and are held
 in place by cotter pins 23 passing through their
 lower projecting ends. 20

As shown in Fig. 4, each of the members 16 is
 formed in the present instance in two parts se-
 cured together by bolts 24, and in these two parts
 are formed the upper and lower halves of the boss
 25 18 through which the shaft 19 extends. The lower
 portion of the member 16 is provided front
 and rear with lugs 25 forming shoulders which
 underlie reverse shoulders on the front and rear
 walls of the hopper formed in the present in-
 stance by strips 26 suitably secured to the inner 30
 faces of said walls. These interlocking shoulders
 prevent elevation of the members 16 from the wear
 plates 14 upon which they normally rest. From
 the upper portion of each of the members 16 ex-
 35 tend arms 27 and 28, these arms respectively lying
 adjacent the rear and front walls of the hopper
 and in each case paralleling the adjacent wall.
 Each of these arms carries a pin 29 which are em-
 braced respectively by the lower bifurcated ends
 40 of a pair of rods 31 and 32 respectively, thereby
 providing a slidable connection between the mem-
 bers 16 and rods 31 and 32. The rods 31 and 32
 extend upwardly parallel to the rear and front
 walls of the hopper, and adjacent their upper ends
 45 are pivotally connected to said walls through the
 medium of studs 33 projecting from the inner wall
 surfaces. The rods 31 and 32 as illustrated in
 Fig. 2 are somewhat spaced from the surfaces
 of the walls.

The opposite ends of the shaft 19 are connected 50
 respectively through links 34 and 35 with arms 36
 and 37, and these arms are in turn respectively
 secured to shafts 38 and 39 supported in brackets
 41 and 42 on the end walls 3 and 4 of the hopper.
 To the lower end of each of the shafts 38 and 39 55

is secured an arm, 43 and 44 respectively, each of which arms is suitably connected, through straps 45 and 46, with connecting rods 47 and 48. The other ends of these rods are connected respectively to crank pins 49 and 51 at the opposite ends of the shaft 12. The pins 49 and 51 lie at opposite sides of the axis of the shaft, so that with rotation of the latter they mutually contribute through the connecting rods and links 10 to a longitudinal reciprocation of the shaft 19. Such reciprocation of the shaft 19 results in a corresponding reciprocation on the wear plates 14 of the members 16 and also in an oscillation of the rods 31 and 32 which as previously described are connected to said members. Each of the connecting rods 47 and 48 is formed with telescoping sections connected through the medium of a pin 52, this pin being adapted to fracture under a predetermined stress. These pins 15 constitute safety elements preventing damage to any of the parts of the foregoing mechanism due to excessive strains developing from any cause.

In operation, coal or other fuel in the hopper passes by gravity through the openings 5 and 25 passages 11 into the series of ram cylinders. The rams reciprocating in said cylinders are withdrawn on the retraction strokes to a point uncovering the lower ends of the passages 11 permitting the fuel to enter the cylinders, and in 30 the forward stroke force this body of fuel from the cylinders into the upper ends of the stoker retorts. Each full reciprocation of the rams involves a similar reciprocation through the mechanism described above of the members 16 and a 35 corresponding oscillation of the pivoted arms 31 and 32. This movement of the members 16 functions to deliver the fuel transversely to the openings 5 and the upper ends of the passages 11, thus effecting a positive feed of the fuel to the 40 ram cylinders and preventing any retardation of the feed due to arching of the fuel over the openings. Oscillation of the arms 31 and 32 contributes towards maintaining a free movement of the fuel in the hopper to the ram cylinders, 45 these arms having an agitating effect preventing undue packing of the fuel in the hopper with a tendency to arch above the discharge openings 5.

It is apparent that the actuation of the members 16 may be effected from other sources than 50 the crank shaft 12, and that there may be numerous changes in structural details without departure from the invention.

I claim:

1. A hopper having in the bottom a plurality of discharge openings through which the contents of the hopper are adapted to pass by gravity, a flat horizontal bearing surface intermediate adjacent openings, a pusher slidably mounted on 5 said surface, a bracket secured to said pusher and means operatively connected to said bracket for reciprocating said pusher transversely between the sides of said openings.

2. A hopper having in the bottom a plurality of discharge openings through which the contents of the hopper are adapted to pass by gravity, a flat horizontal bearing surface intermediate adjacent openings, a pusher slidably mounted on 10 said surface, a bracket secured to said pusher, 15 means operatively connected to said bracket for reciprocating said pusher transversely between the sides of said openings, and guide means for retaining said pushers on said bearing surface.

3. A hopper having spaced side walls and a 20 bottom wall, a plurality of discharge openings in said bottom wall through which the material in the hopper is adapted to pass by gravity, a substantially flat bearing surface intermediate adjacent openings, a pusher slidably supported on 25 said bearing surface, arms pivotally mounted adjacent the side walls of the hopper, and having a 30 slidable connection with said pusher, and means for reciprocating said pusher transversely between the sides of said openings to agitate and positively feed the material thereto, said movement of the pusher causing a swinging movement of said arms thereby effecting a further agitation of the material in the hopper.

4. A hopper having spaced side walls and a 35 bottom wall, a plurality of discharge openings in said bottom wall through which the material in the hopper is adapted to pass by gravity, a substantially flat bearing surface intermediate adjacent openings, a pusher slidably supported on 40 each of said bearing surfaces, a pair of arms extending upwardly along the side walls of the hopper from each of said pushers, and having a 45 slidable connection with the latter, means for pivotally mounting said arms near the upper ends thereof, and means for reciprocating said pushers to agitate and positively feed the material to said discharge openings, said movement of said pusher imparting a swinging movement to said arms thereby effecting a further agitation of the 50 fuel in the hopper.

HERBERT E. PRESTON.
